United States Patent Office.

CHARLES GAUTIER, OF WASHINGTON, DISTRICT OF COLUMBIA.

Design No. 2,699, dated July 9, 1867.

DESIGN FOR A LABEL FOR BOTTLES.

The Schedule referred to in these Letters Patent and making part of the same.

TO ALL WHOM IT MAY CONCERN:

Be it known that I, CHARLES GAUTIER, of Washington, in the county of Washington, and District of Columbia, invented, originated, and designed a new Design for a Label, of which the following is a full, clear, and exact description, reference being had to annexed drawings or specimens, making a part of this specification.

The label consists of two parts, as set forth in the annexed specimens, in the designs and colors intended to be employed, and which fully set forth what I desire to cover by Letters Patent, and which, therefore, need not be more particularly described herein.

What I claim as my invention, and desire to secure by Letters Patent is—

The design for a label, as herein set forth and shown.

C. GAUTIER.
